US00D588603S

(12) **United States Design Patent**
Matsuoka

(10) **Patent No.:** **US D588,603 S**
(45) **Date of Patent:** **** Mar. 17, 2009**

(54) **SET OF BUTTONS FOR A MOBILE COMPUTING DEVICE**

(75) Inventor: **Yoshimichi Matsuoka**, Cupertino, CA (US)

(73) Assignee: **Palm, Inc.**, Sunnyvale, CA (US)

(**) Term: **14 Years**

(21) Appl. No.: **29/282,702**

(22) Filed: **Jul. 26, 2007**

(51) **LOC (9) Cl.** **14-02**

(52) **U.S. Cl.** **D14/456**; D14/247

(58) **Field of Classification Search** **D14/137**,

CLAIM

The ornamental design for a set of buttons for a mobile computing device, as shown and described.

DESCRIPTION

FIG. 1 is a front view of a set of buttons for a mobile computing device;

FIG. 2 is a first isometric view thereof; and,

FIG. 3 is a second isometric view thereof.

The broken lines showing the outline of the mobile computing device are directed to environment and are for illustrative purposes only and form no part of the claimed design.
